UNITED STATES PATENT OFFICE.

JOHN M. DAVIDSON, OF ALLEGHENY, PENNSYLVANIA, ASSIGNOR TO JAMES VERNER SCAIFE, OF SAME PLACE.

DESIGN FOR A FILTER-STRAINER.

SPECIFICATION forming part of Design No. 35,186, dated October 15, 1901.

Application filed September 6, 1901. Serial No. 74,544. Term of patent 14 years.

To all whom it may concern:

Be it known that I, JOHN M. DAVIDSON, a citizen of the United States, residing at Allegheny, in the county of Allegheny and State of Pennsylvania, have invented and produced a new and original Design for Filter-Strainers, of which the following is a specification, reference being had to the accompanying drawing, showing part thereof.

The drawing represents a perspective of my design.

The leading feature of my design consists in the form of the structure.

A is the body of the strainer, which is cylindrical, with circular heads or ends B B, the major portion of the body being cut away to

a point extending below the horizontal center of the body and the two heads connected by a bar C, on which is a neck D, having a screw-threaded extension E.

The space between the heads B B and both edges of the bar C is filled with rods F, which extend into grooves G in the heads B B.

What I claim is—

The design for a filter-strainer substantially as shown and described.

In testimony whereof I affix my signature in presence of two witnesses.

JOHN M. DAVIDSON.
